Primary Examiner — R. Johnson

(57) **CLAIM**

The ornamental design for a musical instrument, as shown and described.

DESCRIPTION

FIG. 1 is a top front perspective view of a musical instrument, showing my new design;

FIG. 2 is a front elevation view thereof;

FIG. 3 is a rear elevation view thereof;

FIG. 4 is a right side elevation view thereof;

FIG. 5 is a left side elevation view thereof;

FIG. 6 is a top plan view thereof; and,

FIG. 7 is a bottom plan view thereof.

The evenly dashed lines shown in the drawings depict portions of the article that form no part of the claimed design. The short-long-short dashed lines depict a boundary of a portion of the article that forms no part of the claimed design.

1 Claim, 4 Drawing Sheets
